UNITED STATES PATENT OFFICE.

WALTER W. JAMES AND THOMAS L. JAMES, OF RAWLES SPRINGS
MISSISSIPPI.

APPARATUS FOR DISTILLING WOOD AND OBTAINING THEREFROM THE DIFFERENT BY-PRODUCTS.

No. 813,302.

Specification of Letters Patent.

Patented Feb. 20, 1906.

Application filed July 6, 1905. Serial No. 268,339.

To all whom it may concern:

Be it known that we, WALTER W. JAMES and THOMAS L. JAMES, citizens of the United States, residing at Rawles Springs, in the county of Perry and State of Mississippi, have invented certain new and useful Improvements in Apparatus for Distilling Wood and Obtaining Therefrom the Different By-Products, of which the following is a specification, reference being had therein to the accompanying drawings.

Our invention relates to improvements in apparatus for distilling wood and obtaining therefrom the different by-products.

The object of our invention is to provide an apparatus of this character which is made of a rectangular form and mounted upon standards at diagonally opposite corners, the lowermost and uppermost parts thereof being the downwardly opposite corners, the retort being heated by steam and steam also being admitted thereto to aid in abstracting therefrom the lighter products contained in the wood.

Another object of our invention is to provide a more simple, cheap, and effective device of this character and in which the same can be more readily charged and in which the same is also more readily discharged.

In the accompanying drawings, Figure 1 is a side elevation of our improved apparatus, partly broken away. Fig. 2 is an end view of Fig. 1, showing the outer casing broken away, showing the positions of the coils.

Referring now to the drawings, 1 represents our retort, which, as shown, is of a rectangular flat box-like form of sheet metal. The retort, as shown, is composed of the two side plates and the edge plates 4, 5, 6, and 7, which form a thin narrow retort, and, as shown, the same is supported on edge at its opposite diagonally-arranged corners 8 and 9 by means of vertical standards 10 and 11, which are of such a length that the lower corner is supported above the base 13 for the purpose hereinafter described.

The retort, as heretofore described, is made of heavy sheet metal and is made perfectly tight, so as to retain the steam-pressure to which it is subjected and which is not a very heavy pressure. Passing transversely through the retort from the side plate 2 to

the side plate 3 is a bolt 4', which prevents the enlarged side plates from spreading or bulging outward under the pressure to which they are subjected.

The edge plate 5 adjacent the upper corner 15 is provided with a cut-away portion extending entirely across the same and forming a charging-opening into which the wood is fed to the retort. The said opening is closed by a door 16, which is hinged at 17, and is provided at its outer end with an opening through which a bolt 18 passes, said bolt being carried by the side plate 4, and thus the door is firmly held closed by means of a nut 19, screwed on said bolt on the outside of the door. The facing of said door is provided with any desired packing to form a steam-tight joint to prevent the steam from leaking from the retort.

The edge 6 at its lower end is provided with an opening extending all the way across the same and forming a discharge-opening whereby the wood is taken from the retort after the by-products have been extracted. The said opening is closed by a door 20, hinged at 21 and held closed by the bolt 22 and nut 23 in the same manner as the charging-door, and is provided with a packing to form the steam-tight joint the same as the charging-door.

Our retort is heated by steam, and in order to fully accomplish this we provide coils 24 and 25, carried by each side 2 and 3 of the retort and supported thereby by the brackets 26. The said coils, as will be clearly seen, are arranged parallel with the sides and adjacent thereto, leaving the central space 27 through the retort and in which the wood to be distilled is placed. The lower ends of said pipes of which the coils 24 and 25 are composed extend outwardly through the side 2 of the retort adjacent its lower end, and said pipes 28 and 29 are in communication with a steam-supply and are provided with valves 30 and 31, by means of which the steam to the coils is regulated. Adjacent said steam-supply pipes for the coils is a pipe 31', which extends inwardly within the retort and has its inner end in communication therewith and which is adapted to supply the live steam to the retort to aid in the distillation of the wood.

The upper end of the retort has in commu-

nication therewith a vapor-conveying pipe 32, which extends upwardly and is provided with a puppet-valve 32', normally held closed, but adapted to be opened by the pressure in the retort. The said pipe is provided with a pipe 33, which is adapted to convey the combined steam and vapor from the wood to the condenser, wherein they are condensed and separated. The said pipe 33 extends downward and communicates with a tank 34, which is partially filled with water, and said pipe extends adjacent the bottom of the tank, so that as the vapor passes into the tank it is cooled, and the products from the wood being lighter than the water they will rise to the top of the tank and can be otherwise separated.

In order to aid in the condensation of the vapor, we provide a water-supply pipe 35, which has a pump 36 in communication therewith, and said pipe intersects the pipe 33, whereby the vapor is engaged by a strong stream of cold water, and said water-supply pipe 35 leads to a tank 37, into which the water is discharged, said water carrying with it a portion of the condensed steam and vapor from the wood, and thus the products from the wood will rise to the top of the tank 37 the same as in the tank 34.

30 The pipe 32 below the valve 30 has a pipe 38 in communication therewith, and the upper end of the pipe 38 carries a steam-gage to indicate the steam-pressure within the retort.

By the structure herein shown it will be seen that the wood being placed in the upper end of the retort fills the space 27 between the coils, and the by-products are abstracted from the wood through the medium of the steam heat from the coils and direct steam-pressure within the retort. When it is desired to employ the retort, the lower door 20 is opened and by the inclination of the side edges 6 and 7 it will be readily seen that the wood by force of gravity will slide down the 45 same and pass from the discharge-opening.

Having thus described our invention, what we claim, and desire to secure by Letters Patent, is—

1. An apparatus of the character described, comprising an angular box-like retort mounted at diagonally opposite corners in a horizontal plane, and steam-coils supported by the sides of the retort, a steam-supply pipe in communication with said retort, the upper and lower diagonally opposite corners having charging and discharging openings respectively. 55

2. An apparatus of the character described, comprising a rectangular retort having its diagonally opposite corners mounted in standards in a horizontal plane, steam-coils vertically disposed within the retort, adjacent the vertically-disposed sides and forming a central space between the same for the reception of the wood to be distilled, a charging-opening adjacent the upper corner, and a discharging-opening carried by the lower diagonally opposite corners and doors for closing said openings. 60 65

3. An apparatus of the character described, comprising a rectangular retort having its diagonally opposite corners mounted in standards in a horizontal plane, steam-coils vertically disposed within the retort adjacent the vertically-disposed sides and forming a central space between the same for the reception of the wood to be distilled, a steam-supply pipe in direct communication with said retort, a discharge-pipe in communication with the upper end of said retort, a puppet-valve within said pipe, and charging and discharging doors carried by the diagonally opposite upper and lower corners. 70 75 80

In testimony whereof we affix our signatures in presence of two witnesses.

WALTER W. JAMES.
THOMAS L. JAMES.
